APPARATUS FOR STITCH REGULATION IN
KNITTING MACHINES

Arthur W. Mutchler, Brooklyn, and Hans J. Straussberger, Middle Village, Long Island, N. Y., assignors to Julius Kayser & Co., New York, N. Y.

Application June 16, 1934, Serial No. 730,896

14 Claims. (Cl. 66—82)

This invention relates to a method of, and an attachment or apparatus for, stitch regulation in full-fashioned knitting machines.

In the knitting of full-fashioned stockings it has been found that variation is liable to and does occur at the commencement of the formation of the heel reinforcement or splice at the sides of the stocking blank. At this point in the knitting operation the speed of the machine is reduced, due to the necessity for the insertion of the reinforcing threads for the heel splice, and it has been found that the portion of the fabric extending between the heel reinforcements in the stocking blank has a comparatively tight stitch, showing a more or less distinct contrast with the stitches of the fabric immediately above the upper extremity of the heel splices. This lack of uniformity is perhaps due to the slowing down of the knitting operation at this point, but, whatever the cause, a contrast in the stitches at this point frequently shows an objectionable line or flaw at the front of the instep or ankle, and as this is a point at which uniformity and smoothness is most desirable, considerable loss has been experienced in the past—and more particularly with the very fine gage sheer stockings at present in demand—due to this lack of uniformity in the size of the stitches.

It is usual practice to provide cams made in sections for automatically controlling the movement of the needle bar to loosen the stitches at each side of the blank to allow for the reinforcement at the heel splices while retaining, for the formation of the loops between said splices, the same stitch regulation as for the main portion of the stocking leg.

One object of our invention is to provide an improved method of stitch regulation for ensuring uniformity of the stitches in the leg and ankle portions of the stocking.

Another object of our invention is to provide a stitch regulating device actuating in connection with the main stitch regulating cam and adapted to control the stitch at the point of commencement of the knitting of the high-splice heel.

A further object of our invention is to provide an additional stitch regulator for opening the stitch to a predetermined degree at the point of commencement of the formation of the high spliced heel. A still further object is to provide a stitch regulator capable of fine adjustment to regulate the stitches to the required extent between the high spliced heel to give the required uniformity with the stitches in the fabric above said heel, and to provide automatic means for

restoring the stitch adjustment on completion of the formation of the instep portion of the leg blank of the stocking.

With these and other objects in view, the invention consists in the novel construction and arrangement of parts hereinafter described, illustrated in the accompanying drawings, and particularly pointed out in the appended claims, it being understood that various changes in the form and constructional details may be made without departing from the spirit of the invention or sacrificing any of the advantages thereof.

In the drawings, Fig. 1 is a front view of the stitch regulator mounted on the usual stitch regulating shaft; Fig. 2 is a side view of the same; Fig. 3 is a side view showing our improved regulator in connection with certain known parts of a full-fashioned knitting machine; Fig. 4 is a view showing the lower part of the blank of a stocking leg; and Fig. 5 is a detail view showing a portion of the micrometer adjustment used in connection with the improved regulator.

Referring particularly to Fig. 3 of the drawings, the usual main cam shaft 1 carries the main cam 2 which actuates the roller 3 mounted on a stud on the lever 4, which latter has a pin 5 that engages a recess in the lever 6 jointed to the needle bar lever 7, all in the usual well-known manner in this type of machine, and—in the usual way—the roller 3 is at certain times prevented from following the contour of the cam 2, the regulator shaft 8 being provided for this purpose with an arm 9 loosely mounted thereon and carrying a roller 10 engaging a cam 11 on the said cam shaft 1.

The said regulator shaft 8 is also provided in the well-known manner with a lever 12 secured thereto, and having a stud 13 for engaging the lower extremity of the lever 4.

Referring particularly to Figs. 1 and 2 of the drawings, the regulator shaft 8 carries the said arm 9 without positive connection thereto, the boss 15 of this arm being located—and held in axial position—between two bosses 16 formed on a fork or bridge-shaped arm 17 secured to the regulator shaft 8 by means of screws 18 so that—in the well-known manner—actuation of the arm 9, through the medium of the cam 11 and roller 10, rocks the regulator shaft through the medium of the arm 17, so that the lever 12 on the shaft 8 engages the lower extremity of the lever 4 and prevents the roller 3 from following the contour of the cam 2, thus regulating the swinging or presser movement of the needle bar.

For imparting the movement of the arm 9 to

the arm 17, as above referred to, a plunger or pin 19 carried by the arm 17 engages the peripheral surface of the cam 20 carried by the arm 9, the upper portion of the arm 9 being forked to receive the said roller 18 and cam 20. The cam 20 is secured upon a pin 21 extending through the forked portion of the arm 9 and also secured on the pin 21 is a notched wheel 22 and a lever handle 23, so that the cam may be conveniently turned by swinging the said handle 23 and is retained in adjusted position by a spring detent 24 secured on the arm 9 and engaging the notches of the wheel 22.

The relative angular positions of the lever arms 9, 17, may be varied by movement of the lever handle 23 so as to regulate the angular position of the regulator shaft 8 relatively to the cam 11 on the shaft 1 for the purpose of regulating the movement of the lever 4 and of the needle bar in the well-known manner, and the following means are also provided for the independent adjustment of the relative angular position of the levers 9, 17.

The plunger 19 is formed with an external screw thread 25 (Fig. 5) engaging a screw-threaded socket in an externally screw-threaded sleeve 26, which latter engages an internally screw-threaded socket in the arm 17, so that adjustment of the arms 9, 17 relatively to each other may be effected by turning either or both of the members 19, 26. One end of the plunger 19 engages the cam 20 as above described, while the opposite end is provided with a notched wheel 27 held in adjusted angular position by means of a spring detent 28 secured on a plate 29 which is in turn secured to one end of the said sleeve 26 and has a pair of projecting pins 30 to serve as handles for the convenient rotation of the plate 29 to turn the members 19 and 26 in unison for the regulation of the stitch at the commencement of the formation of the heel splice.

The plate 29 is provided with a projecting dog or stop 31 secured thereto by a screw 32 and adapted to contact with a stop pin 33 on the arm 17. Secured to the face of the plate 29 and overhanging the peripheral edge thereof is a bracket 34 firmly secured in its proper position by means of a screw 35 and adapted to be engaged by a spring latch 36, held against the periphery of the plate 29 by means of a coil spring 37 mounted upon a pin 38 by which the latch 36 is carried upon a bracket 39 rigidly secured by means of screws 40 to the front face of the said arm 17. Integrally formed with the latch 36 is a tail piece 41 adapted to be engaged by the said lever handle 23 for the disengagement of the latch 36 from the bracket 37 to release the plate 29 and permit the latter to turn in a counter-clockwise direction until the dog 31 engages the stop pin 33, this turning movement being effected by means of a spring 42 in tension between an attachment on the back of the plate 29, and one of the screws 40 securing the bracket 39.

The upward swinging movement of the lever handle 23 is limited by engagement with a hooked end 43 on the bracket 39, and when the leg blank of the stocking 45 has been knitted to the line 46, (Fig. 4) the handle 23 is in the upper position shown at Figs. 1 and 2, and the dog 31 is held in engagement with the stop pin 33 by the action of the spring 42. The plunger or pin 19 having been adjusted within the sleeve 26 to produce the desired form of loop in the stocking leg 45.

During the continuation of the knitting operation to form the heel splice 44 and the instep or

ankle portion 47 of the stocking, the usual practice has been to knit the portion 47 without any modification of the stitch-regulating means from that chosen for the knitting of the blank 45; but, as clearly set forth in the opening paragraphs 5 of this specification, uniformity of stitch in the parts 45, 47 does not result, and whether this lack of uniformity be due to the necessary reduction in speed of the operation of the machine at the line 46, or to the manner in which the threads 10 are laid, or carried to the needles, we have found that the objectionable lack of uniformity can be taken care of and that a uniform fabric can be produced throughout the parts 45, 47 by loosening the stitch to a predetermined extent at the 15 line 46, and for this purpose the dog 31 and bracket 34 are set at predetermined relative positions on the plate 29, and when the line 46 has been reached in the knitting operation, the plate 29 is turned in a clockwise direction by 20 means of the handle 30 until the spring latch 36 engages the bracket 34, thereby modifying to the desired extent the relative angular positions of the arms 9, 17, and regulating the stitch in the manner desired. 25

After the completion of the knitting operation the handle 23 is swung downwardly, or in an anti-clockwise direction (Fig. 2), so as to turn the regulator cam 20 carried by the arm 9 and thus restore the mechanism to position for the 30 knitting of the top section of the next stocking, and this downward movement of the handle 23 automatically releases the latch 36 from the bracket 34, by engagement of the handle 23 with the tail piece 41, and permits the plate 29 to 35 return to its original position in which the dog 31 engages the stop pin 33, thus cancelling the auxiliary adjustment and entirely obviating the possibility of such cancellation being overlooked by the operator. 40

Although the drawings and the above specification disclose the best mode in which we have contemplated embodying our invention, we desire to be in no way limited to the details of such disclosure; for in the further practical application of our invention many changes in form and construction may be made as circumstances require or experience suggests, without departing from the spirit of the invention within the scope of the appended claims. 50

What we claim is:—

1. In a knitting machine of the character described, an apparatus for regulating the actuation of the needle bar mechanism to vary the length of the loops at certain stages in the knitting operation comprising: a member movable to different adjusting positions for controlling the movement of said needle bar mechanism, means releasably engaging said member for retaining the same when moved to one of its adjusting positions, and means connected to said member for automatically moving the same to another of its adjusting positions upon releasing of said first mentioned means. 55

2. In a knitting machine of the character described, an apparatus for regulating the actuation of the needle bar mechanism to vary the length of the loops at certain stages in the knitting operation comprising: a member movable to different adjusting positions for controlling the movement of said needle bar mechanism, spring means acting on said member to normally urge the same to one of its adjusting positions, and latch means engageable with said member for maintaining the same in another of its ad- 60 70 75 75

justing positions against the normal action of said spring means.

3. In a stitch regulating attachment for full fashioned knitting machines, a stitch regulator comprising a stitch regulating member mounted for movement to different adjusting positions for varying the length of the stitch, means for locking said member when moved in one adjusting position, and means for automatically moving 10 said member to another adjusting position when released from said locking means.

4. In a stitch regulating apparatus for full fashioned knitting machines, an attachment for varying the length of the loops in certain portions of the knitted fabric comprising a rotary member movable to different adjusting positions, means for retaining the rotary member in one adjusting position, and means constantly urging 15 said member to another adjusting position.

20 5. In a stitch regulating apparatus for full fashioned knitting machines, an attachment for regulating the length of the stitch in certain portions of the knitted fabric comprising a rotary screw member movable to different adjusting 25 positions, means for retaining the said member in one adjusting position, and spring means for automatically moving said member to another adjusting position.

6. A stitch regulating attachment for full fashioned knitting machines comprising a cam device, a handle for the operation of the cam, in combination with an auxiliary stitch regulator comprising a screw-threaded sleeve, a rotary member movable to different adjusting positions 35 for actuating said sleeve, a spring latch device for retaining the rotary member in one adjusting position, and spring and stop means for automatically moving the rotary member to and retaining it in another adjusting position.

40 7. A stitch regulating attachment for full fashioned knitting machines, comprising a cam device, a handle for the operation of the cam, in combination with an auxiliary stitch regulator comprising a screw-threaded sleeve, a rotary member movable to different adjusting positions 45 for actuating said sleeve, a spring latch device for retaining the rotary member in one adjusting position, and means whereby the said spring latch is actuated by said handle to permit said 50 rotary member to move to another adjusting position.

8. A stitch regulating attachment for full fashioned knitting machines, comprising a cam device, a handle for the operation of the cam, 55 in combination with an auxiliary stitch regulator comprising a screw-threaded sleeve, a rotary member movable to different adjusting positions for actuating said sleeve, a spring latch device for retaining the rotary member in one adjusting position, spring and stop means for moving the rotary member to and for retaining it in another adjusting position, means whereby the said spring latch is actuated by said handle to permit said rotary member to move in said 60 other position, a plunger in screw-threaded engagement with said sleeve and engaging said cam, means for rotating said plunger and means for retaining the plunger in adjusted position for fine adjustment of the regulator.

70 9. A stitch regulating attachment for full fashioned knitting machines, including a stitch regulating cam, a plunger engaging the cam, means for adjusting the plunger to regulate the 75 stitch, a handle for turning the cam relatively to the plunger for adjusting the stitch, and an

auxiliary stitch regulator comprising a screw-threaded sleeve enclosing said plunger and movable to different adjusting positions, means for rotating said sleeve, latch mechanism for retaining the sleeve in one of its adjusting positions, and means for automatically moving the sleeve to another of its adjusting positions. 5

10. A stitch regulating attachment for full fashioned knitting machines, including a stitch regulating cam, a plunger engaging said cam, 10 means for adjusting the plunger to regulate the stitch, a handle for turning the cam relatively to the plunger for adjusting the stitch, and an auxiliary stitch regulator comprising a screw-threaded sleeve enclosing said plunger means 15 for rotating said sleeve and plunger to different adjusting positions to regulate the stitches, means for retaining the sleeve in one of its adjusting positions, and means for automatically moving the sleeve and plunger to another of 20 their adjusting positions.

11. A stitch regulating attachment for full fashioned knitting machines, including a stitch regulating cam, a plunger engaging the cam, means for adjusting the plunger to regulate the 25 stitch, means for turning the cam relatively to the plunger for adjusting the stitch, and an auxiliary stitch regulator comprising a screw-threaded sleeve enclosing said plunger, means for rotating said sleeve to different adjusting 30 positions to regulate the length of the stitch, spring latch mechanism for retaining the sleeve in one of its adjusting positions, and means for automatically moving the sleeve to another of its adjusting positions. 35

12. In a stitch regulating attachment for full fashioned knitting machines, a stitch regulator shaft, an arm fast on said shaft, an arm loose on said shaft, a cam for actuating the loose arm, means whereby movement of said 40 loose arm is imparted to the other arm and to the regulator shaft comprising a cam on the loose arm, a plunger engaging the latter cam and carried by the said fast arm, a handle for the adjustment of the latter cam, means for 45 retaining said cam in adjusted position, screw means for the adjustment of said plunger, means for retaining the plunger in adjusted position in combination with auxiliary stitch regulating means including a sleeve mounted 50 in said fast arm and carrying said plunger, means for adjusting said sleeve, and means for retaining said sleeve in adjusted position.

13. In a stitch regulating attachment for full fashioned knitting machines, a stitch regulator shaft, an arm fast on said shaft, an arm loose on said shaft, a cam for actuating the loose arm, means whereby movement of said 55 loose arm is imparted to the other arm, and to the regulator shaft, comprising a cam on 60 the loose arm, a plunger engaging the latter cam and carried by the said fast arm, a handle for the adjustment of the latter cam, in combination with auxiliary stitch regulating means including a member mounted in said 65 fast arm and carrying said plunger, means for adjusting said member into two positions, means for retaining said member in one of its positions and means for automatically moving same to the other of its positions when released 70 from said retaining means.

14. Stitch regulating means for full fashioned stockings, comprising means for regulating the operation of the needle bar to control the stitch during the knitting of the main por- 75

tion of the stocking leg blank, in combination with independent means for adjusting the operation of the needle bar to a predetermined degree to control the size of the stitches of the portion of the fabric flanked by the heel reinforcements relatively to the size of the stitches of the main portion of the leg blank to insure

substantial uniformity between the stitches in these portions, and means for automatically cancelling said adjustment by the setting of the regulating means for the succeeding operation of the machine.

ARTHUR W. MUTCHELER.
HANS J. STRAUSSBERGER.
